Primary Examiner — Rebekah A Caruso(74) *Attorney, Agent, or Firm* — Gloria Tsui-Yip, Esq.; Gottlieb, Rackman & Reisman, P.C.(57) **CLAIM**

The ornamental design for a brush, as shown and described.

DESCRIPTION

FIG. 1 is a perspective view of our new design; FIG. 2 is a left side elevational view thereof; FIG. 3 is a front elevational view thereof; FIG. 4 is a right side elevational view thereof; FIG. 5 is a rear elevational view thereof; FIG. 6 is a top plan view thereof; FIG. 7 is a bottom plan view thereof; FIG. 8 is another perspective view thereof; and, FIG. 9 is cross-sectional view taken along line 9-9 in FIG. 6.

The broken-line showing of brush tips and specks illustrates environmental structure that forms no part of the claimed design.

1 Claim, 6 Drawing Sheets(56)
